2 Claims. (Cl. 335—89)

This invention relates in general to relay construction, and in particular to a new and useful reversing relay having a rolling reversing contact which is resiliently mounted in a lever member which is actuated by a movable armature.

The invention refers in particular to a relay of a type which may be used for reversing electrical connections such as for switching from a high to a low beam or vice versa in an automobile lighting circuit. Prior to the present invention relays of this type have a basic disadvantage inasmuch as they effect a temporary complete disconnection of the lighting circuit during the switching action so that there will be a darkening of the driver's field of vision in front of the vehicle which could have a very disadvantageous effect on the traffic. A further disadvantage in the relays of the prior art which are used for such purposes is that there is a tendency for them to remain in the neutral position without effecting the switching of the lights for a longer period than is desired, and this may also lead to a dangerous traffic situation.

Further disadvantages in the prior art relay constructions are the form of the contacts. Because the contacts are movable from engagement with one terminal element to engagement with another, there is a migration of material from the contact points and wear, despite the use of a very high grade material such as silver.

A further disadvantage is that when the contact elements are separated, there is a tendency to arcing which will cause a fouling of the contact points.

In accordance with the invention there is provided a relay in which the disadvantages of the prior art are eliminated. In accordance with the invention, the relay includes a first lead or terminal which, for example, may be a positive lead which is connected with at least two negative leads or contact sheets through a displaceable contact which advantageously comprises a roller element. In the preferred arrangement one of the contact elements, for example the positive lead, is arranged on one side of a defined trackway and the two negative leads are arranged on the opposite side in spaced relationship. The movable contact which completes the circuit between the positive and one of the negative leads and provides for contact with both negative leads during the transition period is a rollable contact which is rolled along the trackway defined between the terminals to effect the switching operation. In the preferred arrangement, the terminals which are to be switched are advantageously constructed so that the movable contact will remain in engagement with the first one when the switching operation is already being carried out to complete the circuit to the second and vice versa. For this purpose the contact elements are advantageously formed as sheets which are shaped so that a gap is formed between them which is bridged by the roller contact means. The gap is preferably offset angularly and the roller contact means may comprise two roller elements or a single rolling ball member.

A relay constructed in accordance with the invention thus provides a contact switching means which insures that the circuit to the lights, for example, of an automo-

2

bile is maintained connected to the energy source even during a switching period from one lighting circuit to another. The construction is such that the lighting filament for a low beam, for example, will remain under voltage until the filament for the high beam is supplied with voltage and lights up and vice versa. With the inventive relay construction it is feasible to employ simple brass strips rather than silver as contact sheets.

A feature of the construction is that the brass strips may be easily produced and stamped out as sheet elements with projecting ends which may be used for plug-in connections, for example. Because the reversing contact is designed as a rolling element, there is very little migration of the material of the contact sheets and, in addition, the rolling action produces a self-cleaning of the contact sheets in an advantageous manner so that good current connection is insured at all times.

Because the contact element is a rolling element, there is little possibility that the element will remain in a dead point or neutral position. But even if it does, in accordance with the inventive construction there is still a circuit connection because of the formation of the contact terminals which are always bridged by the movable contact member during the changeover period. Because the movable contact element is biased against the contact terminals, any unevenness of the contact edges of the terminals resulting upon installation will be soon leveled off. The limits of movement of the rolling contact member may be effected in a simple manner by providing abutments formed by inexpensive sheet metal stampings.

In accordance with a further embodiment of the invention the contact terminals are made with grooves defined therealong for accommodating the roller contact means. The positive terminal, for example, may comprise a sheet having a portion with a depression or stamping forming a groove for one roller of a two roller contact means and the opposite or lead away terminals form together a single groove or trackway for the opposite roller. The lead away terminals are spaced apart with the gap formation therebetween being disposed at an angle or obliquely to the longitudinally extending edges of the lead away terminals in order that there will be no possibility that the roller contact members fall into the gap.

Accordingly, it is an object of the invention to provide a reversing relay which includes contact terminals made of inexpensive stampings which are spaced apart in a manner such that a contact element movable thereover will maintain contact with each element during the switchover period and until the switching over is complete.

A further object of the invention is to provide a reversing relay which includes a trackway formed by the spaced contact terminals to be bridged and by the connecting terminal, such as a positive terminal, and wherein there is a movable contact which is operated by an armature for rolling movement over the trackway to effect a changeover of the connection of the positive terminal to one of the other terminals without encountering a period in which the circuit is completely opened.

A further object of the invention is to provide a reversing relay in which the contact switching is effected by a rolling element which rolls over the contact terminals and in which the materials of the contact terminals may be of an inexpensive material such as brass in view of the fact that the circuit changeover is made by the movable contact element without it being lifted completely off one of the contact terminals.

A further object of the invention is to provide a reversing relay which is simple in design, rugged in construction and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there are illustrated and described preferred embodiments of the invention.

In the drawings:

FIG. 1 is a front elevational view of a reversing relay constructed in accordance with the invention;

FIG. 2 is a section taken on the lines 2—2 of FIG. 1;

FIG. 3 is a side elevational view, partly in section, of the relay indicated in FIG. 1;

FIG. 4 is a view similar to FIG. 3 of another embodiment of the invention;

FIG. 5 is a partial section taken along the lines 5—5 of FIG. 4;

FIG. 6 is a view similar to FIG. 1 of another embodiment of the invention;

FIG. 7 is a section taken along the line 7—7 of FIG. 6; and

FIG. 8 is a partial elevational and partial sectional view of the relay indicated in FIG. 6.

Referring to the drawings in particular, the invention embodied therein as indicated in FIGS. 1 to 3 includes a reversing relay for reversing the high and low beams of a motor vehicle which includes a flat plate armature 1 which is mounted by a hinge (not shown) over an electromagnetic coil 9 for movement of its front portion toward and away from the coil 9. The armature 1 carries an actuating arm 13 having an offset portion 13a which is adapted to engage in one of two grooves 10 and 11 of a switch member generally designated 2 for pivotally moving the switch member for actuating purposes. The switch member 2 is pivotally mounted adjacent its upper end on a pivot pin 2' carried by an upstanding bracket 40 which is located at the front of the coil 9. Lever 13 is pivotal within the armature 1 up to a predetermined amount, and upon actuation of the armature it moves downwardly toward the coil 9. The offset portion 13a will engage one side or the other of a pointed cam portion 2a of the switch 2 to move into either the groove 10 or the groove 11 depending on the last position of the switch member. Successive actuation of the armature will effect engagement first with the groove 10 to shift the upper portion of the switch 2 to the position indicated in FIG. 1, and the next engagement by the offset portion 13a will cause engagement in the groove 11 to pivot the switch member 2 to an opposite direction.

In accordance with the invention, the switch member is provided with a hollow lower portion or depression 15 in which is positioned a compression spring 7 which biases a shaft 16 of a roller contact means generally designated 18 downwardly through a supporting sheet 17 located thereabove. In the embodiment of FIGS. 1 to 3, the rolling contact means includes inner and outer disk-shaped contact rollers 3 and 3', arranged at the respective ends of shaft 16. During the movement of the armature 1, the lever 13 is guided in a fork-shaped sheet element generally designated 8 which is secured to the bracket 40. One end 8' of the guide 8 forms an abutment for limiting the movement of the armature 1 and side arm portions 8'' are bent outwardly to limit the pivotal movement of the switch member 2.

In accordance with a further feature of the invention, the relay includes a base plate 19 of insulating material which supports the bracket 40 and the electromagnetic coil 9. Contact terminals in the form of contact sheets 4, 5 and 6 made of an inexpensive material such as brass are formed in an angular configuration or offset and they extend through suitable openings in the base sheet 19 and are secured through the sheet 19 by means of rivets 20. As indicated, the downwardly extending offset portions 4', 5' and 6' which extend below the base sheet 19

are made in the form of plug connections to permit the entire element to be inserted, for example, in a switching circuit.

In the embodiment illustrated, the terminal 4 is a positive terminal and the terminals 5 and 6 are negative terminals which are connected to respective light circuits, for example, to a high beam light circuit and to a low beam light circuit, respectively.

A feature of the construction is that the negative terminal 4 has an extended outer end forming a trackway together with adjacent spaced ends of the contact sheets 5 and 6. The contact sheets 5 and 6 are arranged in end-to-end spaced relationship and their opposite edges are offset so that an offset or maze-like gap 21 is formed. The interior edges 5'' and 6'' of the respective contact sheets 5 and 6 are spaced from and parallel to the outer edge 4'' of the negative contact sheet 4. A gap 27 which is of uniform width is defined between the positive terminal 4 and the negative terminals 5 and 6 and provides a guiding trackway for the roller 3.

The opposite roller 3' on the shaft 16 rides along the opposite outer edges 5''' and 6''' of each of the respective negative contacts 5 and 6. As indicated in FIG. 2, the rollers 3 and 3' may be moved between the two dotted line end positions indicated. In the position indicated at the left, contact is made between the positive terminal 4 and the negative terminal 5. When the roller is rolled by movement of the switch member 2 by the action of the crank 13 produced by the movement of the armature 1, there is rolling contact made first by the inner roller 3 with the contact sheet 6 while the outer roller 3' is still in contact with the contact sheet 5. As the movement of the rollers 3 and 3' progresses to the end position, contact with the contact sheet 5 is broken by the outer contact roller 3' only after the inner contact roller 3 has advanced well along the edges 6'' of the contact sheet 6 to establish firm contact between the contact sheet 6 and the positive terminal 4.

In the embodiment illustrated in FIGS. 4 and 5, there is provided a switch or movable contact member 52 which is pivotally mounted at 52' on a bracket 54 adjacent an electromagnetic coil 9'. The switch 52 includes a recess 15' which contains a spring 7' which urges a spherical member or ball 2 downwardly to engage over fixed contacts or terminals 23, 24 and 25. The ball 22 moves backwardly and forwardly in a gap 26 defined between a first contact 23 and two second contacts 24 and 25. The contacts 23, 24 and 25 are held in position to a base sheet 19' by means of rivets 20'. In this embodiment the trackway defined by the edges 23'' of the first contact and 24'' and 25'' of the second two contacts is of substantially uniform dimension to permit free easy rolling movement of the ball 22. The two second contacts 24 and 25 have ends which are spaced relatively close together so that the contact-making ball 22 will not disengage from one of the contacts 24 until it engages with the other contact 25 or vice versa.

In the embodiments of FIGS. 6 to 8 there is provided a base plate 110 for the relay with contact terminals 111 and 112 connected to respective circuits for the high and low beam of a motor vehicle respectively. The terminals 111 and 112 are connected to a positive terminal 113 through a switch member 220 which is pivotal on a pivot member 221. The switch member includes a cavity or recess 222 having a spring 223 therein which biases roller spring contact means generally designated 25 downwardly. As in the other embodiment, the switching member 220 is actuated by an armature 118 having a lever 119 with an offset portion 119' which engages in one of two grooves A or B. A drive member 117 is located adjacent the armature coil 116 and provides a stop or abutment for the armature 118 and side stops for the switch member 220 as in the other embodiment. The contact terminals 111, 112 and 113 are secured to the base 110 by rivets 114 in a manner similar

to the other embodiment. Each of the contact terminals includes lower plug end portions which extend through openings 110' defined in the base 110.

A feature of the construction of the embodiments of FIGS. 6 to 8 is that the terminals 111 and 112 are placed in spaced relationship and together define a concave groove 29 with a separation or gap 228 being defined intermediate the length thereof caused by the spacing of the terminals 111 and 112. The edges of the terminals 111' and 112' extend obliquely and are substantially parallel to one another. A feature of the construction is that the roller means 225 is provided with roller elements 226 and 228 at each end of the shaft 224 having a curvature which corresponds to the curvature of the groove 29 defined on the two terminals 111 and 112. The wheel 228 is located to ride on a groove 30 defined by the outer edge of the contact terminal 113.

While specific embodiments of the invention have been shown and described in detail to illustrate the application of the inventive principles, it will be understood that the invention may be embodied otherwise without departing from such principles.

What is claimed is:

1. A relay comprising a first contact terminal having an extended edge, at least two second contact terminals spaced from each other and from said first contact terminal, said second contact terminals defining a continuous grooved trackway, each of said second contact terminals having an extended edge alongside the extended edge of said first contact terminal, an electromagnetic coil, an armature movable upon actuation of said electromagnetic coil, a switch contact member pivotally mounted adjacent said armature and in alignment with said first and second contact terminals, said switch contact member being movable in alternately opposite pivotal directions by said armature upon successive operation of said armature by successive actuation of said electromagnetic coil, and roller contact means carried by said switch member bearing in continuous rolling engagement with said first contact and with at least one of said second contacts and being rollable from a position in full engagement with one of said second contact terminals at which the circuit is completed through said roller contact means from said first contact terminal to said second contact terminal to a position at which said roller contact means first engages the other of said second contact terminal without being disengaged from the first of said second contact terminals and thereafter rolls to a further position in which it is in full engagement with the other of said sec-

ond contact terminals and out of engagement with the first of said second contact terminals.

2. A relay comprising a first contact terminal having an extended edge, at least two second contact terminals spaced from each other and from said first contact terminal, each of said second contact terminals having an extended edge alongside the extended edge of said first contact terminal, an electromagnetic coil, an armature movable upon actuation of said electromagnetic coil, a switch contact member pivotally mounted adjacent said armature and in alignment with said first and second contact terminals, said switch contact member being movable in alternately opposite pivotal directions by said armature upon successive operation of said armature by successive actuation of said electromagnetic coil, and roller contact means carried by said switch member bearing in continuous rolling engagement with said first contact and with at least one of said second contacts and being rollable from a position in full engagement with one of said second contact terminals at which the circuit is completed through said roller contact means from said first contact terminal to said second contact terminal to a position at which said roller contact means first engages the other of said second contact terminals without being disengaged from the first of said second contact terminals and thereafter rolls to a further position in which it is in full engagement with the other of said second contact terminals, said first contact element having a longitudinally extending concave groove defined therein, said second contact terminals together defining an elongated concave groove interrupted intermediate its length by the spacing between said terminals, said roller contact means including a roller axle, and a disk-shaped roller element at each end of said axle one of which is rollable in the groove of said first contact terminal and the other of which is rollable along the groove of said second contact terminals.
